CLAIM

The ornamental design for gloves, as shown and described.

DESCRIPTION

FIG. 1 is an elevational palm-side view of a right hand glove
according to the present invention;

FIG. 2 is an elevational backhand view of the glove of FIG. 1
according to the present invention;

FIG. 3 is an alternate elevational palm-side view of the glove
of FIGS. 1-2 being worn by a user according to the present
invention.

FIG. 4 is an elevational palm-side view of a left hand glove
according to the present invention;

FIG. 5 is an elevational backhand view of FIG. 4 according to
the present invention; and,

FIG. 6 is an alternate elevational palm-side view of the glove
of FIGS. 4-5 being worn by a user according to the present
invention.

The broken lines showing the gloves in use are included for
the purpose of illustration and form no part of the claimed
design.
